UNITED STATES PATENT OFFICE.

JONAS NORTHROP AND EDWARD S. STIMPSON, OF HOPEDALE, MASSACHUSETTS, ASSIGNORS TO THE DRAPER COMPANY, OF SAME PLACE AND PORTLAND, MAINE.

LOOM.

SPECIFICATION forming part of Letters Patent No. 641,792, dated January 23, 1900.

Application filed August 25, 1899. Serial No. 728,395. (No model.)

To all whom it may concern:

Be it known that we, JONAS NORTHROP and EDWARD S. STIMPSON, both of Hopedale, county of Worcester, State of Massachusetts, have invented an Improvement in Looms, of which the following description, in connection with the accompanying drawings, is a specification, like letters and numerals on the drawings representing like parts.

This invention relates more particularly to automatic filling-supplying looms wherein the supplying mechanism is operated at the proper time to effect the introduction of a fresh supply of filling—as, for instance, in the loom shown in United States Patent No. 626,187, dated May 30, 1899, the said mechanism being therein shown as operated upon exhaustion to a predetermined extent of the filling in the shuttle. As the fresh supply of filling is transferred the nearly-exhausted filling-carrier is ejected from the shuttle into a box or suitable receptacle, carrying with it the end of filling-thread leading from the edge of the cloth; and our present invention has for its object the production of means to part or sever this filling so that the length of thread extending from the ejected filling-carrier will be as short as possible, the length of filling between it and the cloth being engaged by a thread-clamp or holding device and moved into position to be severed adjacent the cloth by a thread-cutting temple. The piece of thread thus cut in two places between the shuttle and the cloth is retained by the clamp and moved away from the shuttle-path, and before the next change of filling is effected the clamp is opened to release such piece of thread.

We have herein shown one practical embodiment of our invention as applied to a loom provided with filling-supplying mechanism, substantially as shown in United States Patent No. 628,228, dated July 4, 1899, and to coöperate with a thread-cutting temple, which may be of the type shown in United States Patent No. 585,465, dated June 29, 1897; but our invention is not restricted in its application to the exact form of loom shown nor to the particular type of thread-cutting temple herein illustrated.

Various novel features of our invention will

be hereinafter described, and particularly pointed out in the claims.

Figure 1 is a front elevation of a sufficient portion of a loom to be understood, showing 55 filling-supplying mechanism having one embodiment of our invention applied thereto. Fig. 2 is a right-hand side elevation of the apparatus shown in Fig. 1, with the lay-back and the thread parting and clamping means 60 in normal position. Fig. 3 is an enlarged top or plan view of a portion of the loom, showing the thread clamp and parter in operative position just before the end of the filling between the clamp and the edge of the cloth is put into 65 position to be engaged by the thread-cutting temple, also shown. Fig. 4 is an enlarged inner side elevation of the thread clamp and parter in normal position, the device for opening the clamp and parter being broken out. 70 Fig. 5 is a similar view showing the clamp and parter in position to act upon the thread when the transerrer is operated to effect a change of filling, the lay being shown as on its forward beat. Fig. 6 is a sectional detail on the 75 line $x-x$, Fig. 3, of the thread-parter looking to the right. Fig. 7 is an enlarged perspective view of the fixed member or jaw of the thread-clamp, and Fig. 8 is a side elevation of the device which operates to open the 80 clamp and the parter as they are moved in opposition to act upon the filling-thread.

In carrying out our invention the filling-parter is so constructed and arranged that it will only operate when the shuttle is properly boxed, the support upon which the parter is mounted acting as a shuttle-feeler to detect the improper boxing of the shuttle.

As shown in Figs. 1 and 2, the loom-frame A, breast-beam A^4 , the lay A^3 , having the bottom of one of its shuttle-boxes cut away below the self-threading shuttle S, the filling-supplying mechanism comprising connected rotatable plates suitably shaped to hold the filling-carriers b, Fig. 1, the stud ff, the transerrer f', mounted thereon and having the depending end f³ and a finger 21, and the shaft d', adapted to be rocked or partially rotated by or through the action of a feeler (not herein shown) upon exhaustion of the filling in 100 the shuttle to a predetermined extent, are and may be all substantially as shown in United

States Patent No. 628,228, already referred to, the rock-shaft d' herein referred to also corresponding to the similarly-lettered part in Patent No. 626,187, and forming herein, as it does in said patent, a part of the controlling means for the filling-supplying mechanism, operative upon the exhaustion of the filling in the shuttle to a predetermined point. As in said patent, the end f^3 of the transerrer 10 has mounted upon it a headed rocker-stud m , controlled by a spring s , and having an attached arm m^2 , the arm having mounted upon it a notched dog m^3 , provided with a lateral lug m^4 , the dog adapted to be moved into position to be engaged by a bunter C^2 on the lay when a change of filling is to be effected. The loom-frame is provided with a stand A^5 15 at the filling-supplying side, on which is pivoted at 5 a yoke Y , one of its upturned arms y directly engaging the lug m^4 , a lateral stud or projection y^2 on its other arm y and provided with an antifriction-roll 6 being normally engaged by a detent-finger d^3 , fast on the rock-shaft d' and normally maintained 20 in the position shown by a strong spring S^3 , attached at its end to said finger and to the loom-frame, respectively. In the patent referred to one arm of the yoke Y is enlarged and bent rearwardly to form a shuttle-feeler, 25 and in our present invention the corresponding arm y is also upturned and bent rearwardly to act as a shuttle-feeler; but at its extremity it is notched, as at p' , and forms a support for the thread-parter, to be described, 30 and also for the feed-clamp. A sharpened blade p^2 is secured to the inner face of the arm, with its sharp edge just above the bottom of the notch, while a movable blade p^3 is mounted to rock on a stud 10 , fixed in and 35 extended laterally from the inner side of the arm y , said blade being slotted at p^4 , for a purpose to be described, and having a depending heel p^5 at its front end. A lug p^6 extends laterally from the movable blade near its heel, and the said blade moves in a guide 40 45 12, secured to or forming part of the arm y , said guide forming a housing for a spring-detent p^7 , adapted when the blade is in normal open position to catch over its upper corner 50 55 15, (see Figs. 5 and 6), the detent yielding when the blade is positively moved, as will be described, into position to coöperate with the fixed blade p^2 to sever filling between them. A pin 16 is shown best in Fig. 6 as extended across the notch p' near its bottom to prevent the filling-thread from passing too far toward the base portion of the jaws. The stud 10 and a second stud 18 , rigidly mounted in the arm y and extended laterally therefrom parallel to the stud 10 , serve as supports for the fixed member or jaw of the thread-clamp, 60 said jaw being shown separately in Fig. 7 and comprising an upright web c , a lateral extension c' , and a flat foot c^2 , the latter being longitudinally grooved in its upper face, as at c^3 , and intersecting a slot c^4 in the laterally-extended part c' , said slot forming a guide for

the movable member or jaw of the clamp, to be described. The stud 10 is extended through a hole in the web, (not seen in the drawings,) and the latter is maintained against the head of the stud by a spring s^2 , (see Fig. 3,) interposed between the web and a suitable washer w , bearing against the inner face of the movable jaw p^3 of the parter. The spring thus serves the double purpose of a friction-pad for the movable blade, maintaining it open or closed, and to maintain the fixed clamp member in proper position, the stud 18 entering a notch c^5 in the front end of the web and preventing the latter from rotating on the stud 10. The stud 18 extends through the slot p^4 of the movable blade, and the rocking movement of the latter in opening and closing is thus permitted.

As shown in Figs. 3, 4, and 5, the movable member or jaw of the clamp is made as an elongated thin blade c^6 , fulcrumed near its outer end on the stud 18 and having an extension c^7 , which extends beneath the lateral lug p^6 . A spring s^3 (see Fig. 3) is coiled around the stud 18 and held at one end by a lug 25 on the web c and bears at its other end against a pin 30 on the member c^6 to normally maintain the jaw c^6 closed, as shown in Fig. 4, its serrated edge c^8 at such time resting in the groove c^3 of the fixed member or jaw. The upright slot c^4 serves to guide the jaw c^6 as it is rocked, and when the movable blade p^3 of the parter is opened the lug p^6 will engage the extension c^7 of the movable member of the clamp and turn the latter on its fulcrum into relative open position. (Shown in Fig. 5.) The lug p^6 forms a differential connection between the two movable members, for viewing Fig. 4 it will be noticed that the movable member of the clamp will not be moved to open the clamp until after the blade p^3 has been opened and moved far enough to bring the lug p^6 into engagement with the extension p^7 . Conversely the jaw c^6 will close upon its coöperating fixed member before the blades p^2 p^3 will operate to sever a thread between them. A pin 33 in the lateral extension c' crosses the slot c^4 and passes through a cam-slot 35 in the jaws c^6 to limit its movement and prevent accidental displacement.

The normal position of the parter and clamp is shown in Figs. 2 and 4, with the reduced extremity p^{20} of the lug p^6 in position to be acted upon by the device for opening the movable members of the clamp and parter prior to a change of filling, said device being shown best in Figs. 3, 5, and 8. An upturned arm k^x , secured to the bracket A^5 , is bent over at its upper end, as at k , and upon the face of said arm nearest the yoke Y is pivoted at k' a box-like support or carrier k^2 , having secured to or forming a part of its side a cam-lip or switch k^3 , inclined on its underside toward the lay and preferably slightly beveled at its end toward the lay, as at k^4 , a spring s^5 (see dotted lines, Fig. 8) holding the bottom of the carrier up against a stop- 125 130

lug 40, the coil of the spring being supported by a pin 45, fixed in the overhanging end k of the upright arm k^x .

After the thread parter and clamp have operated, as will be described, and returned to normal position the reduced end p^x of the lug p^6 on the blade p^8 wipes over the top of the switch-cam k^3 and depresses the carrier k^2 until the end of the lug snaps past the switch-cam as the parts attain their normal position, (shown in Fig. 4,) the spring s^5 returning the carrier k^2 to such position and elevating the switch, so that when the yoke is swung toward the lay prior to the next change of filling the lug p^6 will travel along the under face of the switch k^3 , and as the latter is held from upward movement by the action of the stop 40 on the carrier k^2 the switch will operate to depress the lug p^6 as it travels along the under face of the switch to first open the parter and thereafter to permit the spring s^3 to open the clamp, so that the latter will be in the position shown in Fig. 5 as the lay nears its forward position, and when the heel end p^5 of the blade p^8 is so depressed the detent p^7 will engage and hold said blade in such position until positively moved therefrom.

We have herein shown the closing of the clamp and parter as effected by means of a bunter C^8 , suitably secured to the lay and adapted to engage the heel p^5 of the movable member of the parter as the lay completes its forward movement. Such engagement with the heel operates to release the blade from the detent p^7 and to permit the spring s^3 to close the jaw c^6 upon the thread before the movable blade of the parter coöperates with its relatively fixed fellow to sever the filling-thread between the clamp and the shuttle then in the shuttle-box, as shown in Fig. 3.

The rock-shaft d' may be rocked or partly turned in any suitable manner—as, for instance, by or through the action of a filling-feeler such as shown in United States Patent No. 626,187, wherein the shaft will be rocked upon exhaustion of the filling in the shuttle to a predetermined extent. When the shaft d' is rocked in the direction of the arrow 50, Fig. 2, the detent-finger d^x will be raised, permitting the spring s to turn the dog m^x into position to be engaged by the bunter C^2 , the lug m^4 at the same time acting through the arm y' to swing the yoke Y upon its fulcrum 5, and if the shuttle is properly boxed the upper end of the arm y will be moved into the position shown in Fig. 5 above and adjacent the raceway of the lay when the latter completes its forward beat. As will be manifest, the movement of the yoke to bring the thread-clamp and parter bodily into position to act upon the filling-thread takes place before the lay completes its forward stroke, the completion of such stroke acting after the thread has entered between the members of the clamp and the parter to first clamp the thread and then to part it between the clamp and the shuttle

and adjacent the latter, so that a very short end of filling will be drawn away by the ejected filling-carrier. The clamping of the thread before the action of the parter prevents twisting or coiling of the thread out of range of the clamp, as would frequently occur were the parter to operate first. The filling having been severed, its loose end is now held between the jaws of the clamp, and the various parts return to their normal positions, the rock-shaft d' being released to permit the spring S^X to depress the detent-finger d^x to thus effect return of the yoke to normal position, and as the clamp still retains its grasp upon the filling end the latter is drawn forward into the path of the cutting device of a thread-cutting temple, (shown only in Figs. 2 and 3,) the latter, as herein illustrated, being the same as shown in United States Patent No. 585,465, the movable member c^2 of the temple-cutter coöperating with a fixed member or blade a^40 , the movable member being hooked, as shown in Fig. 2, to engage and bring the thread against the fixed blade at the next forward beat of the lay when the temple is operated, the hooked end of the movable cutter drawing the filling against the blade a^20 and severing it close to the edge of the selvage of the cloth. The temple as a whole is indicated in Fig. 3 at T. The short piece of thread thus severed is retained by the clamp until the latter is again moved bodily toward the lay prior to the next change of filling, such bodily movement of the clamp resulting, as has been described, in the separation of the jaws, and the piece of thread will be released.

If the shuttle is improperly boxed, when the yoke Y is moved toward the lay the upper end of the arm y will engage the shuttle, operating precisely as does the shuttle-feeler y in United States Patent No. 628,228. It will prevent the movement of the dog m^x into position to be engaged by the bunter C^2 and the transfer of filling will be prevented.

The movement of the yoke toward the lay is regulated by a suitable set-screw 60, mounted in an ear A^{12} of the bracket A^5 , a lock-nut 65 holding the screw in adjusted position, the yoke engaging and being stopped by the screw when its proper operative position is attained, as shown in Fig. 5.

The arm y' of the yoke is herein shown as secured to the other arm y by a bolt 80, extended through an ear y^{12} on the arm y and through a slot 85 in the elbow of the arm y' , so that the latter can be by this construction adjusted relatively to the arm which forms the support for the thread parter and clamp.

Our invention is not restricted to the precise construction and arrangement of parts herein shown and described nor to any particular form of controlling means for the filling-supplying mechanism, such controlling means, as herein illustrated, including the rock-shaft d' and the detent-finger d^x .

Any other suitable form of thread-cutting temple may be used instead of the one herein illustrated.

Having described our invention, what we claim as new, and desire to secure by Letters Patent, is—

1. In a loom provided with filling-supplying mechanism, controlling means therefor, a shuttle adapted to carry a supply of filling, a thread-parter and a thread-clamp, bodily movable by or through the operation of the controlling means into position to act upon the thread of the filling-carrier to be ejected, means to close the clamp and actuate the thread-parter successively upon change of filling, and a device to open the clamp as it is moved into position to act upon the thread.
2. In a loom provided with filling-supplying mechanism, controlling means therefor, a shuttle adapted to carry a supply of filling, a thread-parter and a thread clamp, bodily movable by or through the operation of the controlling means into position to act upon the thread of the filling-carrier to be ejected, means carried by the lay to close the clamp and actuate the thread-parter successively upon change of filling, and a relatively-fixed device to open the clamp as it is moved into position to act upon the thread.
3. In a loom provided with filling-supplying mechanism, controlling means therefor, a shuttle adapted to carry a supply of filling, a thread-parter and a thread-clamp, each having a movable member, a differential connection between said members to move them successively, said thread parter and clamp being bodily movable into position to act upon the thread of the filling-carrier to be ejected, means to engage the movable member of the parter upon a change of filling, and through said differential connection close the clamp upon the thread and thereafter actuate the parter, and a device to put the clamp and parter into operative condition before they are moved into position to act upon the thread.
4. In a loom provided with filling-supplying mechanism, controlling means therefor, a shuttle adapted to carry a supply of filling, a thread-parter and a thread-clamp, each having a movable member, a spring to normally close such member of the clamp, a differential connection between and to move said members successively, said connection acting against the spring to open the clamp, means operating through said connection upon a change of filling to permit closure of the clamp and thereafter to positively operate the parter to part the thread, and a device to open the said movable members of the clamp and parter as the latter are moved into position to act upon the thread.

5. In a loom provided with filling-supplying mechanism, a shuttle adapted to carry a supply of filling, a thread-parter and a thread-clamp, each including a movable member, means operative upon a change of filling to close the clamp upon the thread of the filling-

carrier to be ejected and to thereafter actuate the parter to part the thread while clamped, and an independent device to open said movable members prior to the next change of filling.

6. In a loom provided with filling-supplying mechanism a shuttle adapted to carry a supply of filling, a thread-parter comprising a fixed member and a relatively-movable member having a heel, a thread-clamp comprising a fixed member and a relatively-movable member, a spring to close the latter, a lug mounted on the movable member of the parter, to engage and open the movable clamp member against the action of its spring, a bunter on the lay, to engage the heel of the movable parting member upon a change of filling and move it to first permit closure of the clamp and thereafter to part the clamped thread, and an independent device to open said parter and clamp prior to the next change of filling.

7. In a loom provided with filling-supplying mechanism, controlling means therefor, a shuttle adapted to carry a supply of filling, a thread-parter and a thread-clamp, bodily movable by or through the operation of the controlling means into position to act upon the thread of the filling-carrier to be ejected, the clamp including a movable member, a spring to close it, the thread-parter including a member having a lug to engage and open the movable clamp member against its spring, a relatively-fixed device to engage said lug when the clamp and thread-parter are bodily moved into operative position, to open the clamp and the thread-parter, means to close the clamp upon the thread and to thereafter operate the parter upon a change of filling, and a detent to maintain said clamp and the parter closed as they are bodily returned to normal position.

8. In a loom provided with filling-supplying mechanism, controlling means therefor, a thread-cutting temple located at the same side of the loom with said mechanism, a shuttle adapted to carry a supply of filling, a thread-clamp and a thread-parter, a support therefor actuated upon change of filling by the controlling means to bodily move the clamp and parter into position to act upon the thread of the filling-carrier to be ejected, and means carried by the lay to permit closure of the clamp and thereafter to operate the parter, when they are in operative position, the return of the clamp into normal position bringing the filling end thereby into position to be severed by the temple-cutter.

9. In a loom provided with filling-supplying mechanism, a temple located at the same side of the loom and having a thread-cutter, a shuttle adapted to carry a supply of filling, a thread-parter, movable prior to change of filling into position to part the thread adjacent the filling-carrier to be ejected, a thread-clamp movable into position to engage and hold the thread between the temple and the parter, prior to the action of the latter, means

to move the parter and the clamp into position to operate, the return of the clamp to normal position drawing the parted thread held thereby into position to be severed by the temple-cutter, and means to actuate the parter and the clamp when in operative position, to respectively part and clamp the filling-thread.

10. In a loom provided with filling-supplying mechanism, a temple located at the same side of the loom and having a thread-cutter, a shuttle adapted to carry a supply of filling, a swinging support, means mounted thereon side by side to clamp and to part the thread of the filling-carrier to be ejected upon a change of filling, said filling-supplying mechanism at such time effecting the movement of the support into operative position, the lay, a bunter thereon to effect the successive operation of the clamp and the parter as the lay beats up, and an independent device to open the clamp and the parter as they are moving bodily into operative position, the return of said support to normal position causing the clamp to draw the filling end into position to be severed by the temple-cutter.

11. In a loom provided with filling-supplying mechanism, a thread-cutting temple, a swinging yoke governed by said mechanism, normally-closed thread-clamping jaws and parting-blades mounted upon the yoke, a fixed device to open the jaws and blades as they are bodily moved by the yoke into operative position, the actuation of the filling-supplying mechanism effecting such movement of the yoke, and means mounted on the lay to first close the jaws upon the thread to thereafter close the blades to sever it, the return of the yoke to normal position acting through the holding-jaws to bring the filling end into position to be severed by the temple-cutter.

12. In a loom provided with filling-supplying mechanism, controlling means therefor operative upon exhaustion of the filling in the shuttle to a predetermined extent, a shuttle adapted to carry a supply of filling, a shuttle-feeler, means, including a movable blade, mounted thereon to part the thread of the filling-carrier to be ejected upon change of filling, the lay, a bunter thereon to engage said blade and close it as the lay beats up, a friction device to act upon and retain the blade closed, and an independent device to engage the blade and positively open it prior to the next change of filling.

13. In a loom provided with filling-supplying mechanism, controlling means therefor, a shuttle adapted to carry a supply of filling, a support governed as to its position by said controlling means and movable into operative position upon a change of filling, a thread-clamp mounted on said support and comprising a fixed jaw having a guideway, a pivoted jaw to coöperate therewith and movable in the guideway, and a spring to close the jaw; a thread-parter, including a movable blade, a differential connection between said blade

and the movable jaw, to control the operation of the latter, a device to act upon said connection and open the clamp and parter as they are bodily moved by the support into operative position, and independent means to act upon the blade and through said connection permit first the closure of the clamp upon the thread and thereafter the closing of the blade to part the thread of the filling to be ejected.

14. In a loom, the lay, filling-supplying mechanism, a shuttle-feeler operatively connected therewith, a thread-clamp and a thread-parter mounted on the shuttle-feeler, means to effect the operation of said mechanism upon exhaustion of the filling in the shuttle to a predetermined extent, a device to place said clamp and parter in operative condition as the shuttle-feeler moves toward the lay, to carry the clamp and parter into position to clamp and part the thread of the filling-carrier to be ejected when the shuttle is properly boxed, a bunter on the lay, to close the clamp on the thread and to thereafter actuate the parter as the change of filling is effected, and a thread-cutting temple located at the filling-changing-side of the loom, the return of the shuttle-feeler to normal position operating through the clamp to bring the thread into position to be cut at the temple.

15. In a loom provided with filling-supplying mechanism, controlling means to effect the operation thereof upon exhaustion of the filling in the shuttle to a predetermined extent, a swinging arm having mounted upon it fixed and movable thread-parting blades and clamping-jaws, a spring to close the movable jaw, a lug carried by the movable blade to engage and open said jaw against its spring, a switch-cam to depress the lug and open the clamp and parter as the swinging arm moves them into operative position, and independent means to close the clamp and thereafter to operate the parter to sever the thread adjacent the filling-carrier to be ejected.

16. In a loom, an arm having a thread-receiving notch in its end, fixed and movable blades thereon adjacent the notch, a fixed clamping-jaw and a coöperating pivoted jaw, both mounted on the arm to clamp the thread of a filling-carrier to be ejected, a closing-spring for the pivoted jaw, means to move said arm to bring the blades and jaws into operative position upon exhaustion of the filling to a predetermined extent, a differential connection between the movable blade and jaw, the lay, a bunter thereon to operate through said connection and close the clamping-jaws upon the thread, and thereafter to close the blades and sever it adjacent the filling-carrier to be ejected, and an independent device to open the blades and jaws prior to the next change of filling.

17. In a loom provided with filling-supplying mechanism, a shuttle-feeler, fixed and movable parting-blades mounted thereupon, a friction device to act upon the movable

blade, said blade having a depending heel, a yielding detent to hold the blade open; a thread-clamp mounted on the shuttle-feeler at the side of the blades, said clamp including 5 a pivoted jaw having an extension at one end, a spring to close the jaw; a transverse lug on the movable blade, to engage the jaw extension and rock the jaw against its spring, a device to depress said lug to open the movable blade and the said jaw, means to move 10 the shuttle-feeler into operative position prior to a change of filling, the lay, and a bunter thereon to engage the heel of and close

the movable blade to part the thread of the filling-carrier to be ejected, releasing said 15 blade from its detent, the initial movement of the blade permitting the clamp-jaw to be first closed by its spring.

In testimony whereof we have signed our names to this specification in the presence of 20 two subscribing witnesses.

GEO. OTIS DRAPER.

It is hereby certified that in Letters Patent No. 641,792, granted January 23, 1900, upon the application of Jonas Northrop and Edward S. Stimpson, of Hopedale, Massachusetts, for an improvement in "Looms," an error appears in the printed specification requiring correction, as follows: In line 123, page 4, after the word "end" the word *held* should be inserted; and that the said Letters Patent should be read with this correction therein that the same may conform to the record of the case in the Patent Office.

Signed, countersigned, and sealed this 6th day of February, A. D., 1900.
